[57] CLAIM

The ornamental design for a template for forming panel openings, substantially as shown and described.

DESCRIPTION

FIG. 1 is a front elevational view of a template for forming panel openings showing my new design;

FIG. 2 is a rear elevational view thereof;

FIG. 3 is a top plan view thereof, the bottom being identical;

FIG. 4 is a left side elevational view thereof, the right being a mirror image thereto.

FIG. 1

FIG. 2

FIG. 3

FIG. 4
